LOUIS COATALEN, OF WOLVERHAMPTON, ENGLAND, ASSIGNOR OF ONE-HALF TO SUN-BEAM MOTOR CAR COMPANY LIMITED, OF WOLVERHAMPTON, ENGLAND.

MULTICYLINDER INTERNAL-COMBUSTION ENGINE.

1,235,111.

Specification of Letters Patent. Patented July 31, 1917.

Application filed November 21, 1916. Serial No. 132,641.

To all whom it may concern:

Be it known that I, LOUIS COATALEN, a subject of the King of Great Britain, and resident of Wolverhampton, Staffordshire, England, have invented certain new and useful Improvements in Multicylinder Internal-Combustion Engines, of which the following is a specification.

This invention relates to internal combustion engines, chiefly for aviation purposes, having three rows of cylinders with any desired number of blocks of cylinders in each row. It has for its object to provide a simple and efficient arrangement of the exhaust and inlet pipes which will be conducive to accessibility and reliability. In aviation engines it is very desirable that the exhaust leads be easy and be remote from the carburetors, that the induction pipes be of efficient shape and that the carburetors be easily accessible and their control simple. These requirements are fulfilled by the present invention.

In the accompanying drawings, Figure 1 is a diagrammatic view showing the application of the invention to a three row engine having in each row two blocks of three cylinders in each block.

Fig. 2 is an end view of an engine constructed in accordance with this invention.

Like letters indicate like parts throughout the drawings.

In V-type engines having only two rows of cylinders the requirements specified are fulfilled very simply by locating the carburetors outside the cylinder rows and conducting the exhaust gases upward by short pipes located between the two rows of cylinders, but in an engine having three rows of cylinders the problem is much more difficult.

In this arrangement the inlet pipes A and B for the two central blocks C and D pass between the blocks E F and G H of the outer rows. For instance the front block C of the central row is coupled by a pipe A of this kind with central carbureter A² on the right hand side of the engine and in a line with the carbureters E² F² for the right hand row E F of cylinders. Similarly the rear block D of the central row may have its inlet pipe B passing between those G and H of the left hand row which have their own carbureters G² and H². The three carbureters at each side may be con-

nected together by a control rod X or Y and these two control rods may be operated from a single point Z, so that all the carburetors can be controlled from one point.

The exhaust leads J and K for the two outer rows are arranged on the inner side of those rows and the leads L for the front block C of the central row are on the opposite side to the inlet pipe A for that block, that is to say, on the left hand side while the exhaust leads M of the rear block D of the central row are on the right hand side. If each row of cylinders has a common cam shaft or cam shafts for all the cylinders in that row, in the case of the central row the one cam shaft N carries at N² the inlet valve cams for the block C and the exhaust cams at N³ for the other block D, and the other cam shaft O operates the exhaust valve cams at O² of the block C and the inlet cams O³ of the block D.

The object of this arrangement is to bring the inlet and exhaust pipes of the cylinder blocks C and D on opposite sides as will be clearly seen in Fig. 1.

It will be clear that the inlet pipes A and B are heated as they pass close to the exhaust leads of the adjacent cylinders. The inlet pipes R for the cylinders E F G and H may be heated in any known manner as by providing them with a heating jacket.

The invention has been described as applied to an engine having only two blocks of cylinders in each row, but there may obviously be more than two blocks, each with its own carburetor and inlet pipe.

By this means the carburetors are located at a convenient distance from the exhaust pipes, they are all accessible, and are all capable of operation in a simple manner.

What I claim as my invention, and desire to secure by Letters Patent, is:—

1. In an internal combustion engine, the combination of three rows of cylinders, a plurality of blocks of cylinders in each row, a carburetor for each block of each outer row located on the outer side of its row, and central carburetors for the blocks of the central row located between the carburetors of the outer rows, substantially as set forth.

2. In an internal combustion engine, the combination of three rows of cylinders, a plurality of blocks of cylinders in each row, a carburetor for each block of each outer row located on the outer side of its row,

central carbureters for the blocks of the central row located between the carbureters of the outer rows, and inlet pipes leading from said central carbureters to the blocks of cylinders of said central row which pass between the cylinder blocks of said outer rows, substantially as set forth.

3. In an internal combustion engine, the combination of three rows of cylinders, a plurality of blocks of cylinders in each row, a carbureter for each block of each outer row located on the outer side of its row, central carbureters for the blocks of the central row located between the carbureters of the outer rows, inlet pipes leading from

said central carbureters to the blocks of cylinders of said central row which pass between the cylinder blocks of said outer rows, and cam shafts for said central row each of which operates the inlet valves of one block and the exhaust valves of the adjacent block, substantially as set forth. 20

In testimony whereof I have signed my name to this specification in the presence of two subscribing witnesses.

LOUIS COATALEN.
